US0D1061888S

(12) **United States Design Patent** (10) **Patent No.:** **US D1,061,888 S**
(45) **Date of Patent:** **** Feb. 11, 2025**

(54) **EAR CLEANER**

(71) Applicant: **Zhengzhong Li**, Shaoyang (CN)

(72) Inventor: **Zhengzhong Li**, Shaoyang (CN)

(**) Term: **15 Years**

(21) Appl. No.: **29/926,490**

(22) Filed: **Jan. 30, 2024**

(51) **LOC (15) Cl.** **24-02**

(52) **U.S. Cl.**

USPC **D24/151**

(58) **Field of Classification Search**

USPC D24/107, 108, 111, 119, 127, 128, 133,

(57) **CLAIM**

The ornamental design for an ear cleaner as shown and described.

DESCRIPTION

FIG. 1 is a first perspective view of an ear cleaner showing my design;

FIG. 2 is a second perspective view thereof;

FIG. 3 is a front view thereof;

FIG. 4 is a rear view thereof;

FIG. 5 is a left-side view thereof;

FIG. 6 is a right-side view thereof;

FIG. 7 is an enlarged top view thereof;

FIG. 8 is an enlarged top view thereof; and,

FIG. 9 is an enlarged partial view of portion 9 as shown in FIG. 1.

The dash-dash broken lines are included for the purpose of illustrating portions of the ear cleaner that form no part of the claimed design. The dot-dash broken lines are included to depict areas of enlargement and form no part of the claimed design.

1 Claim, 9 Drawing Sheets
